UNITED STATES PATENT OFFICE

153,557

DESIGN FOR A COMBINED BACKSPLASHER AND TOP FOR ELECTRIC RANGE

Ray C. Sandin, Oak Park, Ill., assignor to Hot-point Inc., a corporation of New York.

Application February 12, 1948, Serial No. 144,451

Term of patent 14 years

(Cl. D81—25)

To all whom it may concern:

Be it known that I, Ray C. Sandin, a citizen of the United States, residing at Oak Park, in the county of Cook and State of Illinois, have invented a new, original, and ornamental Design for a Combined Backsplasher and Top for Electric Range, of which the following is a specification, reference being had to the accompanying drawings, forming a part thereof.

In the drawings,

Figure 1 is a front elevational view of a combined backsplasher and top for electric range, showing my new design;

Figure 2 is an end elevational view thereof;

Figure 3 is a fragmentary plan view thereof, and

Figure 4 is a vertical sectional view thereof, taken in the direction of the arrows along the line 4—4 in Figure 1.

The dominant features of my design reside in the portions shown in full lines.

I claim:

The ornamental design for a combined backsplasher and top for electric range, as shown and described.

RAY C. SANDIN.
